ICE REFRIGERATOR

Alderic C. Legere, Beachmont, Mass., assignor to
 Industrial Engineering Corporation, Boston,
 Mass., a corporation of Massachusetts

Application October 14, 1942, Serial No. 461,910

2 Claims. (Cl. 62—54)

This invention relates to ice refrigerators and especially to a novel construction and arrangement for more efficiently and completely utilizing the cooling effect of the ice and thereby maintaining a lower temperature in the refrigerator and reducing the amount of ice required, all of which results in superior operation at less cost. The ordinary ice refrigerator employs a drain for directly conducting the waste ice water to the outside where any cooling effect left therein is lost. Attempts have been made to trap this ice water and utilize its cooling effect in the refrigerator before passing it to the outside but these attempts have not been such as to gain commercial success and recognition. My invention contemplates a novel construction and arrangement for so conducting this ice water along the walls of the refrigerator as to utilize its cooling effect to the maximum degree in maintaining the refrigerator at a substantially lower temperature thereby reducing the ice melting speed and increasing the efficiency of the refrigerator.

The invention contemplates a refrigerator in which the ice water is conducted from the ice compartment to and over the walls lining the storage compartment. In the preferred construction, a layer of the ice water is provided at the top, bottom and side walls of the storage compartment and the water is conducted over these areas as the ice melts and is permitted to escape at an overflow drain only after its cooling effect has been utilized to the maximum degree. The production of such an improved and superior ice refrigerator comprises the primary object of the invention.

These and other features of the invention will be best understood and appreciated from the following description of preferred embodiments thereof selected for purposes of illustration and shown in the accompanying drawing in which:

Fig. 1 is a vertical sectional view through a refrigerator embodying my invention, the view being taken on line 1—1 of Fig. 2.

Fig. 2 is a vertical sectional view taken on line 2—2 of Fig. 1.

Fig. 3 is a fragmentary view showing a modification of the refrigerator illustrated in Figs. 1 and 2.

Referring first to Figs. 1 and 2 of the drawing, 10 indicates a refrigerator housing including insulated walls 12 and a hinged top cover 14. Beneath the top cover is an ice compartment 16 and a storage compartment 18 therebeneath is normally closed by a door 20.

I have illustrated the three side walls 22, top

wall 24 and bottom wall 26 of the storage compartment as comprising a double walled liner embodying inner and outer walls 27 and 28 held in spaced relation by separator studs or blocks 30. 5 Shelves 31 are supported on the inner walls 27 or in any convenient manner. A perforated ice supporting floor 32 is provided in the ice compartment over the top wall 24. The outer wall 28 of the liner at the top wall slants rearwardly 10 toward the open top end 33 of a pipe 34 which extends downwardly and has its bottom end 35 in communication with the liner at the bottom wall 26. A second pipe 36 has its top end 37 in communication with the liner at the top wall. 15 This pipe extends downwardly and out of the refrigerator at 38 where it can discharge into a drip pan 40.

The melting water from the ice 42 drains onto the top wall 28 from which it enters the pipe 34 20 and passes down to the liner at the bottom wall. The end 37 of the pipe 36 is somewhat lower than the end 33 of the pipe 34 whereby producing a slight water pressure causing the water to travel upwardly through the liner as indicated by the 25 arrows. It will also be noted that the end 37 of the pipe 36 is slightly above the inner wall of the liner at the top 24 whereby always leaving a layer of water on the inner wall.

The ice water passing through the liner absorbs 30 heat from the chamber 18 and is warmest where it passes outwardly through the pipe 36. The interior of the refrigerator is kept constantly cooler by thus lining the chamber with this ice water thereby reducing the ice melting speed and 35 rendering the storage compartment more efficient.

In Fig. 3 I have illustrated a modification of the form of invention shown in Figs. 1 and 2. The chamber in the double walled top liner 60 is independent of the chamber in the liner 62. The 40 liner 62 is continuous over the side and rear walls and the bottom wall of the storage compartment in like manner as the liner illustrated at 22 and 26 in Figs. 1 and 2. The outer wall of the top liner and the ice supporting wall are perforated 45 at 63 to permit passage of water from the melting ice into the top chamber at 60. A pipe 64 (corresponding to pipe 34 in Figs. 1 and 2) is arranged to pass overflow water from the top liner 60 to the bottom wall portion of the liner 62. 50 The entrance end of the pipe 64 is so elevated that a layer 68 of this ice water is trapped in the chamber 60 directly from the melting ice and is maintained in contact with the top liner wall of the storage compartment 18' whereby keeping this wall substantially to the temperature of

melting ice. A pipe 66 (corresponding to pipe 36 in Figs. 1 and 2) is arranged to conduct overflow water from the top end of the liner 62 to the exterior of the refrigerator. It will be apparent that the ice water flowing upwardly through the liner 62 comes quite directly from the ice chamber and maintains the bottom, rear and side walls of the storage compartment at relatively low temperature, the water being heated to a relatively higher temperature as it absorbs heat from the storage compartment and approaches the overflow pipe 66.

The construction, advantages and economies of my invention are believed to be clear and fully apparent.

Having thus disclosed my invention what I claim as new and desire to secure by Letters Patent of the United States is:

1. A refrigerator comprising a housing having a food storage compartment therein and an ice compartment above the storage compartment, the front wall of the housing having a relatively large opening therethrough into the storage compartment, a door for closing the opening, means for receiving ice water from the ice compartment and maintaining a layer thereof continuously over the area at the top extremity of the storage compartment, means for maintaining a layer of said ice water continuously over the area at the bottom extremity of the storage compartment, a pipe for conducting overflow ice water from the first named means to the second named means, means in communication with the second named means for receiving ice water

therefrom and maintaining a layer thereof continuously over the areas at the rear and two adjacent side wall extremities of the storage compartment, and a pipe for conducting overflow water from the top portion of the third named means to the exterior of the housing, the third named means being the sole means for conducting said ice water from the second named means to the second named pipe.

2. A refrigerator comprising a housing having a food storage compartment therein and an ice compartment above the storage compartment, the front wall of the housing having a relatively large opening therethrough into the storage compartment, a door for closing the opening, a double walled water-conducting liner within the housing at and extending along and forming a continuous heat absorbing chamber about the areas at the rear and two adjacent side wall extremities of the storage compartment, means for conducting ice water from the ice compartment to the bottom portion of said chamber, the chamber having no other communication with the ice compartment, and means for conducting overflow water from the top portion of the chamber to the exterior of the housing, whereby the walls at said rear and side areas of the storage compartment are kept at relatively low temperature by the ice water throughout a continuous passage thereof through the chamber from the ice compartment at near melting ice temperature to the overflow water conducting means at relatively higher temperature.

ALDERIC C. LEGERE.
